United States Patent Office

Des. 188,418
Patented July 19, 1960

188,418

LABORATORY TABLE UNIT

Arthur R. Salveson, Garden City, N.Y., assignor to Nor-
bute Corporation, New York, N.Y., a corporation of
Delaware

Continuation of design applications Ser. Nos. 55,742 and
55,732, May 1, 1959. This application Feb. 10, 1960,
Ser. No. 59,336

Term of patent 14 years

(Cl. D16—2)

Fig. 1.

Fig. 3.

Fig. 2.

Fig. 4.

Fig. 5.

Fig. 6.

Fig. 1 is a perspective view taken from one end of a laboratory table unit embodying my new design, the other end not shown being substantially like the end shown;

Fig. 2 is a top plan view thereof;

Fig. 3 is an elevational view of the side opposite that shown in Fig. 1;

Fig. 4 is a perspective view taken from one end of a modified form of the laboratory table unit embodying my new design, the rear thereof, not shown, being substantially plain;

Fig. 5 is a top plan view of the embodiment shown in Fig. 4; and

Fig. 6 is a front elevational view of the embodiment shown in Fig. 4.

This application is a continuation of applications D. 55,732 and D. 55,742, filed on May 1, 1959, now abandoned.

I claim:

The ornamental design for a laboratory table unit, as shown and described.
